UNITED STATES PATENT OFFICE.

JERALD G. DOTY, OF ST. LOUIS, MISSOURI.

DESIGN FOR A LIGHTING COLUMN.

Application filed June 1, 1925. Serial No. 13,616. Term of patent 7 years.

To all whom it may concern:

Be it known that I, JERALD G. Doty, a citizen of the United States, residing at the city of St. Louis and State of Missouri, have invented a new, original, and ornamental Design for a Lighting Column, of which the following is a specification, reference being had to the accompanying drawing forming part thereof.

The drawing illustrates a lighting column of my new design.

I claim:

The ornamental design for a lighting column, as shown.

JERALD G. DOTY.
